UNITED STATES PATENT OFFICE.

FRANK H. NULLMEYER, OF STRUTHERS, OHIO.

DIE HOLDER FOR WIRE-DRAWING BLOCKS.

Application filed March 24, 1925. Serial No. 17,861.

To all whom it may concern:

Be it known that I, FRANK H. NULLMEYER, a citizen of the United States, residing at Struthers, county of Mahoning, and State of Ohio, have invented a new and useful Improvement in Die Holders for Wire-Drawing Blocks, of which the following is a full, clear, and exact description.

The present invention relates to the art of wire drawing, and more particularly to an improved die holder for use in connection with wire drawing blocks.

It has heretofore been customary in this art to use a screw vise arranged to hold dies or plates or other reducing means in position in their holders. These screws either came directly down upon the die or plate from the top of the holder and clamped the die between the screws and the bottom of the holder, or the arrangement was such that the die was clamped between the screws and the forward part of the holder, either of which means caused considerable delay in getting the proper position of the hole in the die in relation with the contact point of the wire drawing block.

By the present invention I have provided a die holder wherein these holding screws which have to be loosened every time the die or plate is moved are eliminated. Wherever I refer to "die", this term will be understood to mean any reducing means used in the art of wire drawing.

In the drawings:

Figure 1 is a plan view of a multi-die holder embodying a preferred form of my invention in position between two wire drawing blocks.

Figure 2 is a longitudinal section through the die holder taken on the line II—II of Figure 1, the wire, however, being shown in an opening in the die;

Figure 3 is a transverse section through the die holder on the line III—III of Figure 2;

Figure 4 is a plan view of a single die holder adapted to hold a die in horizontal position;

Figure 5 is a central vertical longitudinal sectional view of the die shown in Figure 4; and

Figure 6 is a perspective view of a die adapted to cooperate with the holder shown in Figures 4 and 5.

Referring to Figure 1, A and B represent

a pair of wire drawing blocks between which is arranged my improved die holder C, pivoted centrally on a pin D, and having a plurality of dies mounted therein.

Referring to Figures 2 and 3, 2 designates a die having a row of openings a, b, c, d and e therein adapted to be brought selectively into operative relation to an opening 3 in the front of the die holder by moving the die up or down. The die might, however, have only a single opening or it might have a plurality of vertical rows of openings, in which latter case the die would be moved horizontally in order to bring the several rows of openings into cooperative relation to the opening 3.

Back of the die is an adjustable wedge 4 having its front face inclined rearwardly from its lower edge towards its upper edge. The lower portion of the wedge is bifurcated, thereby providing an opening through which the rod or wire to be drawn can pass to the die. Tongues 6 project from the opposite sides of the wedge into horizontal grooves 7 in the sides of the die holder. The wedge has vertical bores 8 in the bifurcated portions thereof, and arranged in these bores

are pins 9 which project below the lower ends of the bifurcated portions and which are held from falling out of the bores by pins 10 which extend transversely of the bifurcated portions and cooperate with reduced portions 11 of the pins 9, whereby the latter are adapted to have a limited vertical movement in the bores. Set screws 12 carried by the upper portion of the wedge engage the upper ends of the pins 9. Tightening these set screws 12 is effective to force the wedge upwardly and to press the pins 9 downwardly against the bottom of the die holder, whereby the upper edges of the tongues 6 are caused to bind against the upper edges of the grooves 7. With this arrangement the wedge 4 can be adjusted towards or from the front of the die holder and clamped in adjusted position.

Arranged between the die 2 and the wedge 4 is a wedge 13 having a handle 14, in the form of a bail, extending from its upper end. The rear face 15 of the wedge 13 inclines forwardly from the top edge of the wedge toward the bottom edge thereof, the angle of inclination of said face corresponding to the angle of inclination of the front face 5 of the wedge 4. The lower portion of the wedge 13 is also bifurcated to

provide an opening through which the wire can pass to the die. By lifting the wedge 13 the distance between the forward inside face of the die holder and the front face of the wedge is increased, so that the die can be removed and replaced by a thinner or thicker die, or the die can be adjusted to bring the desired hole into operative wire drawing position. When the wedge 13 is allowed to drop the die is held in the position desired.

Adjustment of the wedge 4 towards or from the front of the die holder is necessary only in order to cause the wedge 13 to assume a normal position about as shown in Figure 2. Consequently, it will be only necessary to move the wedge 4 towards or from the front of the die holder in cases where there is much variation in the thickness of the different dies being used.

While I have shown in Figures 1, 2 and 3 a die holder adapted to hold a plurality of dies, it will be apparent that the invention is equally adapted to a die holder having a single die. A multiple die holder where a plurality of dies can be held separately is particularly desirable in wire drawing apparatus of the character disclosed, for example, in my co-pending application, Serial No. 657,705, filed August 16, 1923. In an apparatus of this character while drawing through one die to a certain size, it is desirable to get a die into position for succeeding sizes of wire, or to replace a worn-out die with a new one while the wire is being drawn through another die in the holder. In this way considerable saving in time can be effected and an increase in production accomplished by this saving in time ordinarily consumed with holders used heretofore.

Referring to Figures 4, 5 and 6, 17 designates a holder for a single die. This holder is T-shaped, thereby providing an elongated chamber 18 at its front end adapting a die 19, such as shown in Figure 6, to be introduced from either side of this chamber and held by the cooperating wedges 4 and 13 in a horizontal position. The die may have a plurality of horizontal rows of openings 20 which may be selectively brought to register with the opening 3 by adjusting the die up or down or horizontally.

An important advantage of my construction of die holder over those in common use at present, is in the location of the opening or openings into which the die or dies are introduced. Such openings or openings being at the top of the holder, the lubricants contained in the holder can not work out and be wasted as is common with holders ordinarily used, which have openings at the side. These side openings must be large enough to receive the largest die which it is expected to use, and when a smaller die is used for a finer gauge of wire to be drawn,

which is the usual practice, the opening between the back of the die and the holder is increased by the difference between the thickness of a thick die and that of a thin one, which allows the lubricants to work out of this opening, unless packed with waste by the wire drawer, which is sometimes done with a loss in time and a consumption of waste.

While I have shown and described certain preferred embodiments of my invention, it will be understood that the invention is not limited to its illustrated embodiments, but that it may be otherwise embodied within the scope of the appended claims.

I claim:

1. Wire drawing means, comprising a die holder open at its top, a die of substantially uniform thickness adapted to be inserted and removed through the opening in the top of the holder, and means for clamping said die against a face of the holder, said means comprising a vertically adjustable wedge having a face parallel with the face of the holder which is to engage the die, said face of the holder engaging one face of the die and the parallel face of the wedge engaging the opposite face of the die, substantially as described.

2. Wire drawing means, comprising a die holder open at its top, a die adapted to be inserted and removed through an opening in the top of the holder, and means for clamping said die against the face of said holder, said means comprising a wedge spaced from said face, and a vertically adjustable wedge arranged between said die and said first wedge and engageable therewith, substantially as described.

3. Wire drawing means, comprising a die holder open at its top, a die adapted to be inserted and removed through an opening in the top of the holder, and means for clamping said die against the face of said holder, said means comprising a wedge adjustable towards and from said face, means for holding said wedge in adjusted position, and a vertically adjustable wedge arranged between said die and said first wedge and engageable therewith, substantially as described.

4. Wire drawing means, comprising a die holder open at its top, a die adapted to be inserted and removed through an opening in the top of the holder, and having a plurality of reducing openings therein, and means for clamping said die against the face of said holder with the desired opening in operative position, said means comprising a vertically adjustable wedge engageable with said die, substantially as described.

5. Wire drawing means, comprising a die holder open at its top, and having a vertical wall with an opening therethrough for the passage of the wire being drawn, a die adapt-

ed to be inserted and removed through the opening in the top of the holder and having a plurality of reducing openings therein adapted to be registered selectively with the opening in said wall by adjusting the die in said holder, and means for clamping said die in adjusted position against the inner face of said wall, said means comprising a wedge adjustable towards and from said wall, 10 means for holding said wedge in adjusted position, and a vertically adjustable wedge arranged between said die and said first wedge, substantially as described.

6. Wire drawing means, comprising a die 15 holder pivoted to swing on a vertical axis and having a plurality of compartments each adapted to receive a die through an opening in the top thereof, and means in each compartment for clamping a die against a wall 20 thereof, said means comprising a vertically adjustable wedge engageable with said die, substantially as described.

7. Wire drawing means, comprising a die 25 holder pivoted to swing on a vertical axis and having a plurality of compartments each adapted to receive a die through an opening in the top thereof, and means in each compartment for clamping a die against a wall 30 thereof, said means comprising a wedge spaced from said wall, and a vertically adjustable wedge arranged between said die

and said first wedge, substantially as described.

8. Wire drawing means, comprising a die 35 holder having an opening in one wall thereof, a die having a reducing opening therein, and means for clamping said die against said wall with its reducing opening registering with the opening in said wall, said means comprising a removable wedge engageable 40 with said die, substantially as described.

9. Wire drawing means, comprising a die 45 holder having an opening in one wall thereof, a die having a reducing opening therein, and means for clamping said die against 50 said wall with its reducing opening registering with the opening in said wall, said means comprising a wedge spaced from said wall and an adjustable wedge arranged between said die and said first wedge and engageable 55 therewith, substantially as described.

10. Wire drawing means, comprising a die holding box open at the top and adapted to contain a lubricant for the wire drawing 60 operation, a die adapted to be inserted into the box through the opening in the top thereof, and a wedge within the box for clamping the die in position, substantially as described.

In testimony whereof I have hereunto set 60 my hand.

FRANK H. NULLMEYER.
